DESIGN FOR AN ILLUMINATING FLOOR LAMP

Roland A. Manning, Milwaukee, Wis., assignor
to Moe-Bridges Corporation, a corporation of
Wisconsin

Application May 16, 1938, Serial No. 77,227

Term of patent 14 years

To all whom it may concern:

Be it known that I, Roland A. Manning, a citizen of the United States, residing at Milwaukee, in the county of Milwaukee and State of Wisconsin, have invented a new, original, and ornamental Design for an Illuminating Floor Lamp, of which the following is a specification, reference being had to the accompanying drawing, forming part thereof.

Fig. 1 is a front perspective view of an illuminating floor lamp with the standard fragmentarily shown, showing my new design;

Fig. 2 is a bottom plan view partly in section taken along the line 2—2.

I claim:

The ornamental design for an illuminating floor lamp, substantially as shown.

ROLAND A. MANNING.
